UNITED STATES PATENT OFFICE.

LEVI PARKER HAZEN, OF CINCINNATI, OHIO.

METALLIC LATHING.

Application filed October 26, 1925. Serial No. 65,021.

This invention relates to metallic-lathing adapted for convenient, economic, fire-proof and other effective use in connection with the surfacing, on one or both sides, of inside 5 walls, outside walls, floors and roof construction and, more particularly, to that type of metallic-lathing that is composed of dovetail cross-section channels or depressions formed in sheet-metal to both strengthen and 10 stiffen it and provide interlocking and abutting means that have recesses or chambers for the keying and bonding of the plaster or cement aggregate used as the surfacing or covering of said wall, floor and roof parts of 15 buildings.

The invention consists in the provision of both longitudinally interlocking and abutting channeled sheet-metal strips that are of dovetail cross-section and adapted to make a 20 dovetail anchor or spreader-key of the plastic material used in a building-structure, and on one or both sides of the part of the structure that is to be coated or covered with either plaster, concrete, gypsum, or like materials, as circumstances or conditions may 25 require.

The details of structure of the specific forms of metallic-lath now presented and devised by me will be fully hereinafter described and then pointed out in the claims that follow.

In the accompanying sheet of drawings—

Figure 1 is a fragmentary perspective view of one of several forms of my dovetail-channeled metal-lath; Fig. 2, a similar fragmentary perspective view of another of the said several forms; Fig. 3, a perspective view showing a series of closely-jointed metal-lath units or strips of both said forms seen 40 in Figs. 1 and 2; Fig. 4, an end elevation of a series of dovetail cross-section metal-lath units seen in Fig. 2; Fig. 5, a cross-section of an abutting series of dovetail cross-section metal-lath strips seen in Fig. 1; Fig. 6, a 45 sectional view similar to Fig. 5; and Fig. 7, a miniature end view of a roll or coil of metal lath-units made and connected in series as displayed in Fig. 5.

The body-portion of the metal lath unit or strip herein is best shown, taken by itself, in Fig. 2 and is designated by the letter A, which letter is carried constant throughout all the views in the sheet of drawings. This body-portion comprises a plane, flat main-member or single unit strip that has inwardly-bent longitudinal edges a, a, at an

acute angle to complete a dovetail cross-section of the narrow metal strip that imparts rigidity and strength, as well as to provide chambers or recesses for anchoring 60 in what is commonly known as key-spreading of the plaster or other plastic-surfacing for walls and ceilings of building-structures. Holes a' are preferably punched at intervals apart in the said main-member of the lath-unit for convenience in setting and driving the fastening-nails B into place in the timber C, the latter being either a studding, joist, rafter, or other mounting-support for the lath-unit and the coating whatever the plastic 65 may be, or its purpose, whether wall, ceiling, or floor to be covered. This body-portion forms the nucleus about which the improvements herein evolve, and I will now proceed to describe briefly the details of the 70 several correlated structures that are employed in obtaining the best results in connection with wall, ceiling and floor parts of buildings.

In Fig. 1 is shown a lath-unit that is made 80 up essentially of the said dovetail body-portion A that has lateral obtuse-angled extensions D, along both of its opposite longitudinal edges. These extensions D are made up of base-portions 8 formed integral with the 85 lower edges of the inwardly-turned members a, a, of the body-portion A, and outwardly-flared vertical flanges 9, the degree of flare practically corresponding to that of the said members a, a, and thereby providing 90 a channel along the opposite edges of the said dovetail body-portion A. In Fig. 3 is shown how the structure seen in Fig. 1 is secured by means of said nails B to the supporting-timber C, such nails being inserted 95 through the holes a' in the dovetail body-portion A, and thence into the upper narrow edge or side-face of the said timber C. In this view (Fig. 3) a pair of said lath-units of Fig. 1 is compactly or closely jointed in 100 parallel with one of the dovetail members A seen in Fig. 2, with the inwardly-turned members a, a, of said member A resting or seated in the angle of the lateral obtuse-angled extensions D, whereby the upper corner 105 edges of the series of said jointed body-portions A approach closely together to maintain a continuous surface for the adhesion of a plastic adapted for floor work in particular, that needs no key-spreading thereof 110 to anchor it in supported place as would be necessary in wall and ceiling uses.

In Fig. 4 is shown an interlocking structure composed of reversely-arranged dovetail duly-corresponding body-portions or metal lath-members A, the inwardly-turned edges or members *a*, *a*, of each member A being in lapping and abutting engagement with its reversely-set or inverted member A and thereby forming a very strong and feasible array of key pockets or chambers on both sides of a wall or other part of the building-structure for the surface-coating of plaster or other desired plastic material that is suited to the purpose of the user in the formation of the said building-structure. In this view is shown the plastic as being designated by the letter E in the upper course only, but it will be understood that the plastic can be used on both sides and including the lower course also.

In Fig. 5 is shown what may be termed an abutting pair of a modified form of jointed series of metal lath-units comprising my invention herein, each lath-unit having in common with the other a dovetail body-portion A, a counterpart of Fig. 2, and with lateral right-angled extensions D along both of its longitudinal edges, somewhat similar to the obtuse-angled extensions D in Fig. 3 but with the upper flange-portion *d* a trifle higher along one edge than the upright flange-portion *e* along the other edge thereof, so that, when assembled, the shallow flanges *e* abut each other and the higher flanges *d* abut each other to correspond. Allowance is thus made in the dovetail-form channel E', which is the result obtained when the shallow abutting-members *e* are brought together in placing the metal lath-units of this modified structure (Fig. 5) for the reception of the plastic E. The said plastic becomes keyed or anchored in the said channel E', the same as in the other dovetail-form channels of the body-portion A of each lath-unit and, also, in the dovetail-form of channel F that will result when the higher abutting-members *d* are brought together in placing laths of this modified structure (Fig. 5) in position for use. Besides, I use a narrow transverse metal strip G in this modified form (Fig. 5) at suitable intervals apart to more stably unite or bind the series of abutting metal lath-units, such strips being each conveniently made up of a number of short lengths that are wrapped or coiled at their meeting ends, as shown at *g* and with such resultant coil-joints turned downwardly into the dovetail-form channels E' wherein the shallow abutting-members *e* are present and ordinarily serve to support the coil-joint. The said strips G are further spot-welded at *g'* to each body-portion A in the series of lath-units in this structure (Fig. 5) for adding stability thereto.

In Fig. 7 is shown how the coupled-up structure shown in Fig. 5 can be made into

extended lengths and coiled or rolled into round bundles or rolls for convenience in handling and shipping.

In Fig. 6 is shown still another form, which is practically a modified replica or 70 duplicate of that shown in Fig. 5, but in which the lateral right angled extensions D have shallow flange-portions *e* along one longitudinal edge and a downwardly-turned right-angled extension *f* along its other 75 right-angled longitudinal edge *f'*, so that, in assembling, the extension *f* laps upon the abutting edges *e* and *f'* within the dovetail-form channels E', the result of bringing together the said abutting edges *e* and *f'* when 80 placing the metal lath-units in series for the anchored-reception of the plastic. The lapped form of joint in this view (Fig. 6) serves to strengthen the same and obviate spreading of the lath-units away from each 85 other transversely, thus avoiding cracks in the plastic after setting, which is highly efficient and important in all plastic parts of building-structures.

In summing up many of the advantages 90 acquired in the use of the sheet-metal lath-units herein I here state that there is no waste, as the "cuttings" can be used on smaller surfaces and secured to supports very readily by means of nails or the like; 95 the material used is readily obtained and of a cheap and permanent, fireproof nature; that said material takes the place of wood which is a very decided factor in the conservancy of lumber and of the forests; that the metal laths are unbreakable and, when packed in the usual size bundles of one-hundred (100), are easy to handle; that said metal laths, in shipping, will carry a low 100 freight rate and with no insurance being necessary; that when the said metal laths are made up in the roll-form seen in Fig. 7 they may be quickly applied to flat surfaces and thereby a decided saving of labor and 105 time accomplished; that the metal lath herein is fire-proof and its use in structures 110 serves its purpose in reducing rates of insurance throughout the structure, and otherwise becomes a permanent fire-proof, vermin-proof and non-shrinkable part of the building-structure, and adds greatly to its 115 strength and permanency; and the laths herein, being "machine-made", can be very economically and expeditiously manufactured in large or small quantities as desired. 120

It will be here observed that a saving of plastic material is effected whenever no keys or anchors are necessary in the use of my metal lath-units herein, which is always an important feature in the use of any material 125 that is costly and should not in any event be wasted.

In Fig. 1 is shown a pair of intersecting slits H made in the sheet-metal for upsetting or depressing inwardly by means of a 130

hammer or the like and adapted to provide a pocket or recess for anchoring or keying a quantity of the plastic-covering of the metal lath, especially on upright walls and overhead ceilings. In Fig. 2, however, is shown another form of key or anchor recess that is provided or made possible by slitting the metal in an associated pair of angular-U-shape cuts that result in a pair of tongues 10 I, I, which are adapted to be depressed by means of a hammer or other suitable implement and thereby accommodate a supply or entrance of a quantity of the plastic material in surface coating or covering the walls 15 or ceilings of a building-structure.

I claim:—

1. A metal-lath structure comprising a single sheet-metal hollow unit or body-portion of dovetail cross-section and having an 20 L-shape lateral extension formation along its opposite longitudinal edges.
2. A metal-lath structure comprising a single sheet-metal hollow unit or body-portion of dovetail cross-section having L-shape 25 lateral extension formations along both of

its longitudinal edges and adapted to longitudinally abut similar formations in the assembling of a series of like dovetail metal laths for the reception of a surface coating or covering and the anchoring of plastic 30 material on one or both sides of the series.

3. A metal-lath structure comprising a single sheet-metal hollow unit or body-portion of dovetail cross-section having L-shape lateral extension formations along its opposite longitudinal edges that are of several heights and adapted to abut in parallel use with like units for providing longitudinal auxiliary channels of dovetail cross-section between adjacent dovetail body-portions and 35 transverse metal strips jointed together in coil or wrapped ends and further spot-welded or likewise secured to the plane member of each of said body-portions for connecting or binding the series of metal laths in 40 jointed and wrappable or roll form, substantially as shown and described.

In testimony whereof I hereby affix my signature.

LEVI PARKER HAZEN.
